CLAIM

The ornamental design for a process chamber tray, as shown.

DESCRIPTION

FIG. 1 is a top perspective view of a process chamber tray of the present invention;

FIG. 2 is a perspective view showing one side of a process chamber tray of the present invention;

FIG. 3 is a perspective view showing another side of a process chamber tray of the present invention;

FIG. 4 is a perspective view showing the top of a process chamber tray of the present invention;

FIG. 5 is a perspective view showing the bottom of a process chamber tray of the present invention;

FIG. 6 is a perspective view showing the front end of a process chamber tray of the present invention; and,

FIG. 7 is a perspective view showing the back end of a process chamber tray of the present invention.
